OIL WELL CASING HEAD AND TUBING
HANGERJohn Lemley, Midland, Tex., assignor to Gray
Tool Company, Houston, Tex., a corporation of
Texas

Application December 30, 1937, Serial No. 182,618

20 Claims. (Cl. 166—14)

The present invention relates to oil well completion equipment, and particularly to a casing head and tubing hanger which make possible increased flexibility in the manner in which the well may be flowed.

One of the principal objects of the invention is to provide equipment of the above type wherein in the well may be flowed simultaneously or independently from the tubing through a Christmas tree and from the tubing through a regular casing head side outlet or outlets, while at the same time the well may also be permitted to relieve itself of flow from the casing through another of the regular side outlets in the casing head.

In the accomplishment of the above, I have devised a novel form of tubing hanger having a side passage therein adapted to be aligned with one of the regular casing head side outlets, said hanger being so constructed that another of the regular casing head side outlets will not be blocked off when the tubing is hung, so that the well may be flowed simultaneously from the tubing through a regular casing head side outlet, as well as from the casing through a regular casing head side outlet, without the necessity of providing additional side outlets in the casing head.

In the drawings, which are illustrative of preferred forms which the invention may take, and are in no sense restrictive,

Figure 1 is a vertical sectional view through a well casing head and control equipment mounted thereon, showing the manner in which the hanger is lowered to its seat in the completion of a well;

Figure 2 is a vertical sectional view of the casing head, showing the tubing hung therein, with the Christmas tree in position and the well ready for flowing;

Figure 3 is a side elevational view of the hanger;

Figure 4 is a cross section of the hanger on the line 4—4 of Figure 3;

Figure 5 is a cross section of the hanger on the lines 5—5 of Figures 3 and 7;

Figure 6 is a sectional view of the casing head similar to Figure 2, showing a modified form of the invention;

Figure 7 is a vertical sectional view through the casing head taken along the line 7—7 of Figure 6;

Figure 8 is a horizontal sectional view of the casing head taken along the line 8—8 of Figure 6.

It is customary to flow an oil well through tubing hung in the casing head controlled by various valves and fittings associated together in a superstructure which is mounted on the casing head. This assembly of valves and fittings is usually called a Christmas tree. While the well is flowed through the Christmas tree, it is essential that there be provided side outlets from the casing head to relieve pressure from the interior of the casing outside of the tubing, which outlets may be used, if desired, to flow the well from the casing.

Referring to Figures 1 and 2, the ordinary casing of a well is indicated at 8, and secured to the upper end thereof is a casing head 10. There may be several casings, one inside another, each provided with an appropriate casing head, and with a hanger for hanging each casing in its head. For the sake of simplicity, I have disclosed only a single outside casing, 20 with its casing head. The casing head is provided with a pair of regular side outlets 12 and 14, said outlets having their axis in the same horizontal plane. In the particular embodiment disclosed, the said outlets are in alignment with 25 one another, on opposite sides of the casing head. These outlets normally provide conduits of flow from the casing, and are equipped respectively with flanges 16 and 18, to which are adapted 30 to be secured as by bolts, as shown, the respective flanges 20 and 22 of control valves 24 and 26. It will be understood that it is desirable to have as few side outlets in the casing head as possible, as when the well is completed, the fluid therein will be under tremendous 35 formation pressure, and even though the side outlets are controlled by valves during the flow life of the well these valves may become leaky, thus presenting a dangerous nuisance and making necessary their replacement, which in itself 40 is a dangerous operation.

In Figure 2 the hanger 30 of the present invention is shown seated in the casing head. The casing head has a bore 32 slightly larger than the bore of the casing 8, and in the upper end 45 of the casing head and above the side outlets 12 and 14 this bore tapers outwardly as at 34 providing a conical seat for the reception of the hanger. Above this seat the casing head is equipped with a circular flange 38 which serves 50 as a foundation either for the control equipment shown in Figure 1, to be hereinafter described, or for the Christmas tree disclosed in Figure 2 and which will also be hereinafter discussed. Extending laterally through the flange 55

38 and operable from the exterior of the casing head when equipment is mounted thereon, are a plurality of locking screws 40, said screws having tapered ends 42 which engage the beveled surface 44 extending around the upper end of the hanger. The locking screws are threaded through openings in the flange 38, and suitable packing 46 is placed around the screws and held in sealing engagement therewith and with the bore through the flange 38 by glands 50 which are threaded into a counter bore in the flange.

The hanger 30 supports the conventional flow tubing 52, which extends to a point adjacent the bottom of the well, generally within or above the screen or strainer carried by the casing 8, and through which the oil from the well flows under the natural formation pressure.

Mounted on the casing head and secured thereto by flange and bolt connections of like size, is a master manifold valve 54, this valve being the conventional master control used on Christmas trees. A circular metal gasket 56 is provided between the flange of the valve 54 and the flange 38 of the casing head to provide a seal. This valve may be considered as constituting the Christmas tree, or it may be the master control for other valves of the Christmas tree mounted above the same.

It has been the practice to hang the tubing by means of the hanger in the casing head, position the Christmas tree on the casing head, and then flow the well from the tubing through the valves and fittings of the Christmas tree. The casing head side outlets such as 12 and 14 have generally only been used for flowing the well or relieving pressure from the casing, and to permit the returns during the drilling and washing operations to be discharged from the casing head.

It is contemplated that wells now being completed may flow under their own natural pressure for many years. During the flow life of these wells, it is probable that many changes will be made in the manner in which the oil is conveyed from the well. For instance, the usual Christmas tree above the master manifold 54 includes two or more conduits of flow, usually provided by mounting a T or cross or other manifold fitting of the same character above the master manifold valve, so that the oil may be flowed simultaneously or independently through different flow lines leading to separate tanks, pipe lines and so forth. A plurality of such flow lines are necessary, for the sake of convenience, and because when a valve or fitting becomes leaky in one flow line, it is desirable to be able to close that line off while the valve is replaced, while still maintaining the flow of oil from the well through another line. To entirely close off a well for the repair of valves or fittings is not good practice, as the cessation of flow may permanently injure the well.

An elaborate arrangement of valves in the Christmas tree is to be avoided, not only because of the expense involved in leaving such equipment as a permanent part of the Christmas tree structure, but also because each valve itself is an additional hazard which may become leaky or blow out, resulting in loss of control of the well, or at least in the loss of time and money necessary to effect repairs.

The present invention has been devised to reduce to a minimum the number of valves and fittings necessary to be left as a part of the well structure, while still providing a marked flexibility in the manner in which the well may be flowed during its life.

Referring to Figures 2, 3, 4 and 5, the hanger 30 of the present invention has an enlarged cylindrical head 60 and a downwardly and inwardly tapered seating portion 61 which is adapted to closely engage the seat 34 of the casing head. A pair of packing rings 62 encircle said tapered portion, said rings being embedded in grooves in the wall of the hanger. These rings are forced into sealing engagement with the casing head seat by the weight of the tubing, and also by the pressure of the bevelled ends 42 of the locking screws 40. Below the lowermost packing ring 62, the hanger has a substantially cylindrical portion 64 (Figure 4) throughout a half part of its circumference, this portion not being as large as the casing head bore 32, so that fluid from the casing may pass upwardly around the hanger through the passage 66, and discharge through the regular side outlet 14 of Figure 2.

As particularly shown in Figures 2 and 4, a half part 68 of the circumference of the lower part of the hanger is of increased diameter, and the outer surface of this portion of the hanger is of the same curvature and intimately engages the wall of the bore of the casing head adjacent the side outlet 12. This portion 68 of the hanger is grooved as shown in Figures 2 and 4, to receive substantially circular packing members 70 which extend completely around the side outlet 12 in the casing head when the hanger is hung therein. Within the packing rings 70 and extending through the side wall of the portion 68 of the hanger is a hanger side passage 72, which is of the same diameter as the casing head outlet 12, and is adapted to be aligned therewith when the tubing is hung.

With this arrangement, and when the tubing is hung, the well may be flowed from the tubing through the Christmas tree under the control of the master manifold valve 54, and simultaneously or independently from the tubing through the side outlet 12 of the casing under the control of the valve 24 shown in Figure 1. At the same time, the well may be flowed either simultaneously or independently with this tubing flow from the casing through the side outlet 14 in the casing head under the control of the valve 26 shown in Figure 1, it being apparent that the construction of the hanger is such that the side outlet 14 is not blocked off when the tubing is hung.

The construction of the completion equipment shown in Figure 2 and as previously described, thus provides three separate conduits of flow from the well, and at least two separate conduits of flow from the tubing. The well may be effectively controlled with the use of only three valves on the well structure. The well may be ordinarily flowed through the Christmas tree under control of the master manifold valve 54 with the valve 24 closed, and when it is desired to make any repairs or replacement in valves or fittings beyond the master manifold valve 54, the conduit of flow from the tubing through the side outlet 12 may be cut in by opening the valve 24, after which the master manifold valve 54 may be closed and any repairs or replacements desired can be effected in any Christmas tree or flow lines extending from the well therefrom with perfect safety, and at the same time without cutting off the flow of the well through the tubing. As stated above, there is grave danger of ruining a well by completely cutting off flow therefrom, and it is highly desirable to be able to at all times continue the flow through the tubing.

This invention permits the simultaneous flow-

tion, and that they carry as an integral part thereof all necessary means to form a seal and close off the upper end of the casing head. Thus, the hanger not having any protruding parts, may be conveniently lowered to its seat through the control equipment on the casing head, as shown in Figure 1, while maintaining control of the well.

The invention of this application is an improvement in the apparatus and methods for completing wells described and claimed in application Serial No. 736,635, Roger Smith, filed July 24, 1934, and application Serial No. 58,821, Robert A. Mueller and Roger Smith, filed January 13, 1936.

Various changes may be made in the construction disclosed herein without departing from the invention.

I claim:

- 20 1. In well completion apparatus, a casing, a casing head having a bore, said bore including a hanger seat, said casing head having a plurality of side outlets at the same level therein, a Christmas tree control valve positioned above said casing head, a tubing in said casing, a hanger on said tubing adapted to engage said seat and suspend the tubing in the well, said hanger having means for simultaneously flowing the well from the tubing through one of said outlets and from 30 the tubing through said valve, and providing for relieving pressure from the well at the same time from said casing through another of said outlets.
- 25 2. In well completion apparatus, a casing, a casing head having a bore therethrough, said bore including a hanger seat, said casing head having a pair of side outlets with their axes substantially in the same horizontal plane, a tubing in said casing, a hanger on said tubing adapted to engage said seat, said hanger having a bore 40 in alignment with said tubing, a lower extension on said hanger having a side wall in sealing engagement with said casing head bore adjacent one of said outlets, said extension being reduced adjacent the other of said outlets to permit flow 45 of fluid from said casing through said other outlet, said hanger having a side passage from its bore to its outer wall opposite said first mentioned outlet, whereby the well may be flowed from said tubing through said first mentioned side outlet.
- 50 3. In well completion apparatus, a casing, a casing head having a bore therethrough, said bore including a hanger seat, said casing head having a pair of diametrically opposed side outlets at substantially the same level in the casing head, a tubing in said casing, a hanger on said tubing adapted to engage said seat, a lower extension on said hanger having a side wall in sealing engagement with said casing head bore adjacent the outlet on one side thereof, said 55 extension being reduced adjacent the outlet on the other side of said casing head to permit flow of fluid from said casing through the latter outlet, said hanger having a side passage from its bore to its outer wall opposite said first mentioned outlet, whereby the well may be flowed from said tubing through the outlet on one side of said casing head, and well pressure relieved from said casing through the outlet on the other side of the casing head.
- 60 4. In well completion apparatus, a casing, a casing head having a bore therethrough, said bore including a hanger seat, said casing head having a pair of side outlets with their axes substantially in the same horizontal plane, a tubing 65 in said casing, a hanger on said tubing adapted

to engage said seat to suspend the tubing in the well, means surrounding said hanger forming a seal between the same and the bore of said casing head to close off the upper end of said casing, said hanger having a bore in alignment with said tubing, a lower extension on said hanger having a side wall in engagement with said casing head bore adjacent one of said outlets, said extension being reduced adjacent the other of said outlets to permit flow of fluid from said casing through the latter outlet, said hanger having a side passage from its bore to its outer wall opposite said first mentioned outlet, and means surrounding said first mentioned outlet and forming a seal between the bore of the casing head and the outer wall of said hanger, whereby the well may be flowed from said tubing through said first mentioned outlet.

5 5. A hanger for suspending tubing in a well having a longitudinal bore therethrough, and 20 having an outside surface comprising a seating portion, packing means on said seating portion of the hanger extending laterally around the same, a side passage opening through the wall of the hanger from the bore to the outer surface 25 thereof, and packing means on the outer surface of said hanger completely surrounding said passage.

6. A hanger for suspending tubing from the casing head of a well, said hanger having upper 30 and lower ends and a longitudinal passage therethrough, a side passage opening through the wall of said hanger intermediate the ends thereof from said longitudinal passage to the outer surface of the hanger to provide a channel of flow 35 from the interior of the hanger, the outer wall of the hanger opposite said passage being reduced from the lower end thereof to the level of said passage to provide a longitudinal channel of flow along the outside of said hanger when the 40 latter is seated in the casing head.

7. A hanger for suspending tubing in a well having a longitudinal bore therethrough, said hanger having a downwardly tapered head to seat in the casing head of a well, packing means 45 on the outer wall of said hanger at the downwardly tapered portion thereof extending laterally around the hanger for forming a seal with a seat in the casing head, said hanger having a semi-cylindrical portion below its downwardly 50 tapered portion for engaging a wall of a casing head, a side passage opening through the wall of the semi-cylindrical portion of the hanger from the bore to the outer surface thereof, and packing means on the outer wall of said semi-cylindrical portion of the hanger completely surrounding said passage.

8. A hanger for suspending tubing in a well having a curved outer surface to conform with and seat in the curved bore of a casing head, said 60 hanger having a longitudinal passage therethrough, a side passage opening through the wall of the hanger from said longitudinal passage to the outer curved surface of the hanger, and packing means on the outer surface of the hanger 65 completely surrounding said side passage to seal against the curved bore of the casing head around said side passage.

9. A hanger for suspending tubing in a well having a curved outer surface to conform with 70 and seat in the curved bore of a casing head, said hanger having a longitudinal passage therethrough, a side passage opening through the wall of the hanger from said longitudinal passage to the outer curved surface of the hanger, packing 75

ing of the well from the tubing through a regular casing head side outlet, and also from the casing through a regular casing head side outlet without the necessity of providing additional casing head side outlets below the conventional ones shown at 12 and 14. A great majority of the casing heads now in practical use have their side outlets positioned with their axis in a single plane, and usually only two casing head side outlets are provided on opposite sides of the head in alignment with one another. If the hanger 30 were of such construction that when lowered to its seat it blocked off the flow from the casing to the side outlet 14, it would be necessary to provide additional casing head side outlets below those shown at 12 and 14 in order to provide for the safe relief of fluid from the casing. This is highly undesirable, as the number of outlets and valves therefor should be kept at a minimum.

The hanger of the present invention is adapted to be lowered to its seat while maintaining a seal between the casing and tubing at all times, and if desired, while a seal is provided within the tubing until the hanger is seated. As shown in Figure 1, the casing head is adapted to receive thereon control equipment of a now well known construction. This control equipment comprises a master drilling valve 76 and a pair of blow out preventers 78 and 80 mounted on the casing head 10 as a foundation, and secured thereto in sealing engagement by flange and bolt connections of like size. The bore 82 through this control equipment is as large as the maximum bore of the casing head, and is somewhat larger than the internal diameter of the casing, so that a drill or other device as wide as the casing may be lowered through this equipment and into the well while a seal is maintained by the blowout preventers between the drill string and the casing.

In Figure 1, the hanger 30 is disclosed being lowered to its seat, said hanger being attached as previously described to the upper end of the tubing 52, and is lowered by means of a length of tubing 84 which is screwed into the upper threaded portion 86 of the bore of the hanger as shown in Figure 2. During insertion of the tubing, if dangerous pressure exists in the well, a tubing seal such as a frangible disk may be provided near the lower end of the tubing, and the lower end of the tubing is inserted to position above the master drilling valve 76 while the latter is closed, and the blowout preventers engaged with the tubing, after which the master drilling valve is opened and the tubing lowered into the well, the blowout preventers 78 and 80 being alternately operated to pass tubing collars and the like. The external diameter of the hanger 30, while being greater than that of the bore of the casing 8, is not quite as large as the bore 82 of the control equipment, so that said hanger may be lowered to its seat while control of the well is maintained between the casing and the tubing by alternate operation of the blowout preventers 78 and 80 as portrayed in Figure 1.

The hanger may be lowered to the position shown in Figure 1 with blowout preventer 78 in engagement with the tubing 52, after which the blowout preventer 80 may be engaged with the lowering pipe 84, followed by the lowering of the hanger to its seat. The hanger is locked in its seat by operation of the locking screws 40, which were retracted when the hanger was lowered into its seat.

When the hanger is seated and locked, the control equipment, including the master drilling

valve and blowout preventers, may be relegated to the position of accessories, after which the master manifold valve may be positioned on the casing head, with any further control equipment in the nature of valves and fittings disposed beyond said master manifold valve. The well may then be flowed after a weight is dropped through the tubing to destroy the frangible seal in the lower end thereof. In lieu of a frangible disc to seal the tubing, a removable spear or removable back pressure valve may be disposed therein, the latter permitting a downward flow of fluid through the tubing to wash the well while providing against reverse flow therethrough due to the formation pressure. Such a valve may be removed, without losing control of the well, after the Christmas tree is mounted on the casing head.

While it is preferred to only provide a pair of casing outlets, and to employ a hanger of the type shown in Figures 2 through 5 in practicing this invention, increased flexibility of flow or manifolding may be provided by employing a casing head 90 shown in Figures 6, 7 and 8, which has more than two side outlets. In this modification, the casing head has two pairs of opposed outlets 92 and 94 having their axis in substantially the same horizontal plane, and a modified form of hanger 96 is provided with a pair of opposed tubing flow passages extending laterally through its wall, as shown at 98 and 100, and both the said passages are surrounded by packing rings 102 in the outer wall of the hanger, as described in connection with Figure 3. The hanger of this modified form of the invention is circular in cross section as shown in Figure 5, and is identical with the hanger of the preferred form of the invention where it seals with the casing head, but the lower portion of the hanger is provided with two opposite semi-cylindrical sealing surfaces 103 and 104 of substantially the same radius as the interior of the casing head bore 105 adjacent the openings 98 and 100. Between these sealing surfaces the hanger is cut away on each side as shown at 106 and 108, so that when the hanger is seated, pressure from the casing may be relieved, or fluid may flow therefrom upwardly through the cut away portions 106 and 108 discharging through the casing head side outlets 94, as shown in Figures 7 and 8. Appropriate grooves are provided in the side wall of the hanger in the sealing surfaces 103 and 104 to receive the packing rings 102, which rings completely surround the hanger passages 98 and 100 and the casing head side outlets 92, thus completely isolating the latter outlets from the casing.

With this arrangement, the well may be simultaneously or independently flowed from the tubing through the Christmas tree and from the tubing through either or both of the casing head side outlets 92. At the same time, the well may be flowed either simultaneously or independently with this tubing flow from the casing through either or both of the casing head side outlets 94. The master manifold valve 54 controls flow through the Christmas tree from the tubing, and each of the casing head side outlets will be equipped with valves to control flow through conduits extending therefrom as will be understood from the description of the principal embodiment of the invention. If desired, any of the casing head side outlets may be closed by bull plugs if desired.

It will be noted that both types of hangers shown in this application are of simple construc-

means on the outer surface of the hanger completely surrounding said side passage to seal against the curved bore of the casing head around said passage, and packing means on the outer surface of the hanger extending laterally around the same above said side passage to seal against the curved bore of the casing head.

10. A hanger for suspending tubing in a well having an outer surface to conform with and seat in the bore of a casing head, said hanger having upper and lower ends and a longitudinal passage therethrough, a side passage opening through the wall of the hanger intermediate the ends thereof from said longitudinal passage to the outer surface of the hanger, and packing means on the outer surface of the hanger completely surrounding said side passage to seal against the bore of the casing head around said side passage, the outer surface of the hanger outside of said packing which surrounds said side passage being reduced from the lower end of the hanger to the level of said side passage to provide a longitudinal channel of flow along the outside of the hanger when the latter is seated in the casing head.

11. A hanger for suspending tubing in a well having an outer surface to conform with and seat in the bore of a casing head, said hanger having upper and lower ends and a longitudinal passage therethrough, a side passage opening through the wall of the hanger intermediate the ends thereof from said longitudinal passage to the outer surface of the hanger, packing means on the outer surface of the hanger extending laterally around the same above said side passage to seal against the bore of the casing head, and packing means on the outer surface of the hanger completely surrounding said side passage to seal against the bore of the casing head around said side passage, the outer surface of the hanger outside of said packing which surrounds said side passage being reduced from the lower end of the hanger to the level of said side passage to provide a longitudinal channel of flow along the outside of the hanger when the latter is seated in the casing head.

12. A hanger for suspending tubing in a well, said hanger tapering inwardly from its upper toward its lower end, and having an outer surface shaped to conform with and seat in the bore of the casing head, said hanger having a longitudinal passage therethrough, a side passage opening through the wall of the hanger from said longitudinal passage to the outer surface of the hanger, and packing means on the outer surface of the hanger completely surrounding said side passage to seal against the bore of the casing head around said side passage.

13. A hanger for suspending tubing in the casing head of a well, comprising a unitary fitting having upper and lower ends and being tapered from its upper toward its lower end, said hanger having an outer surface of substantially the same size and shape as the bore of the casing head to seat in and form a seal therewith, and having a longitudinal passage therethrough, a side passage opening through the wall of the hanger from said longitudinal passage to the outer surface of the hanger, the outer surface of said hanger having a groove therein completely surrounding said side passage, and packing in said groove to form a seal against the bore of the casing head around said side passage.

14. In well completion apparatus, a casing head having a bore therethrough and having side outlets

lets from said bore, a tubing supporting hanger having an outer surface of substantially the same size and shape as said casing head bore to seat in and form a seal therewith, said hanger having a longitudinal passage therethrough and a side passage from said longitudinal passage to the outer surface of the hanger, said side passage being in alignment with one of said outlets, and packing means entirely surrounding said one of said outlets and compressed between said casing head bore and the outer surface of said hanger for forming a seal around said one of said outlets.

15. In well completion apparatus, a casing head having a bore therethrough and having side outlets from said bore, a tubing supporting hanger having an outer surface of substantially the same size and shape as said casing head bore to seat in and form a seal therewith, said hanger having a longitudinal passage therethrough and a side passage from said longitudinal passage to the outer surface of the hanger, said side passage being in alignment with one of said outlets, packing means entirely surrounding said one of said outlets and compressed between said casing head bore and the outer surface of said hanger for forming a seal around said one of said outlets, and packing means on the outer surface of the hanger extending laterally around the same above said side passage compressed between said casing head bore and the outer surface of said hanger for forming a seal above another of said outlets.

16. In well completion apparatus, a casing head having a bore therethrough and having side outlets from said bore, a tubing supporting hanger having an outer surface of substantially the same size and shape as said casing head bore to seat in and form a seal therewith, said hanger having upper and lower ends and a longitudinal passage therethrough, a side passage opening through the wall of said hanger intermediate the ends thereof from said longitudinal passage to the outer surface of said hanger, said side passage being in alignment with one of said outlets, and packing means entirely surrounding said one of said outlets and compressed between said casing head bore and the outer surface of said hanger for forming a seal around said one of said outlets, the outer surface of said hanger outside of said packing which surrounds said one of said outlets being reduced from the lower end of said hanger to the level of another of said outlets, to provide a longitudinal channel of flow from the casing between the outside of said hanger and the bore of said casing head to said last named outlet.

17. In well completion apparatus, a casing head having a bore, said bore including a hanger seat, said casing head having a plurality of side outlets at the same level therein, a tubing supporting hanger adapted to engage said seat and suspend the tubing in the well, said hanger having a longitudinal passage therethrough for flowing the well from the tubing through the Christmas tree, and having means for simultaneously flowing the well from the tubing through one of said outlets, and providing for relieving pressure from the casing of the well at the same time through another of said outlets.

18. In well completion apparatus, a casing head having a bore, said bore including a hanger seat, said casing head having a plurality of side outlets at the same level therein, a tubing supporting hanger adapted to engage said seat and sus-

pend the tubing in the well, said hanger having a longitudinal passage therethrough for flowing the well from the tubing through the Christmas tree, and having means for simultaneously flowing the well from the tubing through one of said outlets, and providing for relieving pressure from the casing of the well at the same time through another of said outlets, means forming a seal between said hanger and said casing head bore around said first-named tubing outlet, and means forming a seal between said hanger and said casing head bore above said last-named casing outlet.

19. A hanger for suspending tubing in the casing head of a well, having an outer surface of substantially the same size and shape as the bore of the casing head to seat in and form a seal therewith, and having a longitudinal passage therethrough, a plurality of side passages opening through the wall of the hanger from said longitudinal passage to the outer surface of the hanger, and packing means on the outer surface of the hanger completely surrounding each of

said side passages to seal against the bore of the casing head around each of said side passages.

20. A hanger for suspending tubing in the casing head of a well, having an outer surface of substantially the same size and shape as the bore of the casing head to seat in and form a seal therewith, said hanger having upper and lower ends and a longitudinal passage therethrough, a plurality of side passages opening through the wall of the hanger intermediate the ends thereof from said longitudinal passage to the outer surface of the hanger, and packing means on the outer surface of the hanger completely surrounding each of said side passages to seal against the bore of the casing head around the same, the outer surface of the hanger being reduced between said side passages from the lower end of the hanger to the level of said side passages to provide longitudinal channels of flow along the outside of the hanger when the latter is seated in the casing head.

February 21, 1939.

JOHN LEMLEY.

It is hereby certified that error appears in the printed specification of the above numbered patent requiring correction as follows: Page 1, first column, line 13, for the word "of" read or; page 2, first column, line 32, for "wall" read well; and that the said Letters Patent should be read with this correction therein that the same may conform to the record of the case in the Patent Office.

Signed and sealed this 28th day of March, A. D. 1939.

Henry Van Arsdale

(Seal)

Acting Commissioner of Patents.
